UNITED STATES PATENT OFFICE

OSCAR STUESSE, OF ST. LOUIS, MISSOURI

RAT TRAP

Application filed July 27, 1929. Serial No. 381,473.

My invention relates to improvements in rat traps, and has among its objects the production of such devices which shall be simple, inexpensive, sturdy, reliable, and efficient and satisfactory for use wherever found applicable.

Another object of my invention is to provide a rat trap which may be folded up when not in use, to a substantially flat, thin, compact package, so that the same may be conveniently stored away until desired.

Another object of my invention is to provide a device of the kind described, in which no springs are needed to hold the parts in their "set" relationship, so that the traps may have a very long period of usefulness.

Many other objects and advantages of the construction herein shown and described will be obvious to those skilled in the art to which this invention appertains, from the disclosures herein given.

To this end, my invention consists in the novel construction, arrangement and combination of parts herein shown and described, and uses mentioned, and more particularly pointed out in the claims.

In the drawings, wherein like reference characters indicate like or corresponding parts throughout,

30 The figure is a perspective view of my improved device, as viewed in operative position.

Referring more particularly to the drawing, wherein I have illustrated a preferred embodiment of my invention, P indicates a heavy plate, of metal, wood or the like, one end of which rests upon the ground or other suitable supporting surface, and the other end of which is maintained uplifted, somewhat as shown. Obviously, when there is a rat beneath the board and it is permitted to fall thereon, the rat will be killed.

The device for maintaining the plate in its "set" position will now be described.

45 The framework of the trap comprises three main parts, these being the elongated, strips or rod elements 1, 2 and 3. The upright element 1 is adapted to rest on the supporting surface on which the lower end of the plate

under side or surface of the plate P, as shown, and thereby maintain the latter in its tilted position.

The element 2 extends laterally across the element 1, and is pivoted thereto, at a point intermediate its ends to intermediate the ends of the latter. This pivotal connection is preferably formed by forming a tubular portion 4 out of the material of the rod 1 and a similar tubular portion 5 out of the material of the rod 2, in any suitable manner, and then inserting the pin 6 through the registering openings 4 and 5. In this construction, the strips 1 and 2 will be foldable so as to lie flat, in the same plane.

The third element 3 is interposed between the elements 1 and 2, so that movement of the latter may be transmitted therethrough to the former to release the plate P. Element 3 is preferably hinged or pivoted at one end 7 by forming a tubular portion thereat, similar to the portions 4 and 5 previously described, and the adjacent end of the element 2 is similarly formed as at 8, a pin 9 extending through the bearings thus formed.

The other or free end of the element 3 abuts against the element 1 above its pivotal connection with the element 2, the element 1 having a projection 10 formed thereon, to act as a stop to be engaged by the free end of the element 3 and prevent accidental upward movement of the latter therewith.

Obviously, any downward movement of the outermost end of the element 2 will actuate the element 3 forwardly or longitudinally, to thereby cause the latter to move the upright element 1 forwardly about its lowermost end, and thereby release the plate from support, and permit the latter to fall.

Any suitable bait may be suspended from the forward end of the element 2, as at 11, and if desired, a platform 12 may be suspended from the element 2. This platform not only steadies the bait, providing more ready access thereto, but in addition, the weight of the rat thereon, will of itself, actuate the parts to release the board. A resilient means, such as the spring 13, may be placed beneath the platform 12, for steadyng contact with the supporting surface.

When it is desired to put the device away, out of service, the three elongated elements may be folded together so as to lie substantially flat, and occupy but little room, making a very convenient assembly.

Having thus described my invention, it is obvious that various immaterial modifications may be made in the same without departing from the spirit of my invention; hence I do not wish to be understood as limiting myself to the exact form, construction, arrangement, and combination of parts herein shown and described, or uses mentioned, except as limited by the claims.

What I claim as new and desire to secure by Letters Patent is:

1. A rat trap comprising an upright element adapted to be mounted on a supporting surface and support a heavy plate at its upper end, a second element having one end removably abutting the first element, and a third element movably pivoted to said first element and operably connected to the second element to actuate the latter longitudinally to move the first element out of supporting contact with the plate to release the latter.
2. A foldable rat trap comprising an upright element adapted to rest on a suitable supporting surface and supportingly engage a heavy plate at its upper end, a second elongated element pivoted to said first element intermediate its ends, and a third elongated element pivoted at one end to said second element above its pivotal connection with said first element, whereby movement of the second element will be transmitted through the third element to actuate said first element to release said plate from supported position.
3. A rat trap comprising an upright rod adapted to be placed on a supporting surface and support the uplifted end of a heavy plate thereover, a second rod extending laterally of said rod and pivoted thereto, a third rod between said rods to transmit movement therebetween, one end of the third rod abutting the first rod, and means on said first rod to engage the abutting end of the third rod to prevent accidental upward movement of said ends of the latter.
4. A rat trap comprising an upright plate-supporting element adapted to be supported on a suitable surface, a laterally extending rod pivoted to said first element, a third rod having one end pivoted to one end of the laterally extending rod and the other end in releasable abutting engagement with the upright element, whereby movement of the laterally extending rod will rock the upright element about its surface engagement to thereby release said plate, a bait platform depending from said second rod, and resilient means at the underside of said platform and adapted to engage said supporting surface.
